US00D608777S

(12) **United States Design Patent**
Yoon

(10) **Patent No.:** **US D608,777 S**
(45) **Date of Patent:** ** *Jan. 26, 2010

(54) **NOTEBOOK COMPUTER**

(75) Inventor: **Sang-Won Yoon**, Seoul (KR)

D578,525 S 10/2008 Yoon
D580,432 S 11/2008 Yun et al.
2005/0041378 A1* 2/2005 Hamada et al. 361/680

(73) Assignee: **Samsung Electronics Co., Ltd.**, Suwon, Kyunggi-do (KR)

(*) Notice: This patent is subject to a terminal disclaimer.

(**) Term: **14 Years**

(21) Appl. No.: **29/313,323**

(22) Filed: **Dec. 26, 2008**

(51) **LOC (9) Cl.** **14-02**

(52) **U.S. Cl.** **D14/315**

(57) **CLAIM**

The ornamental design for a notebook computer, as shown and described.

DESCRIPTION

FIG. 1 is a top front perspective view of a notebook computer showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 4 Drawing Sheets
